(57) **CLAIM**

The ornamental design for a wash basin, as shown and described.

DESCRIPTION

FIG. 1 is a perspective view of the wash basin of the subject invention;

FIG. 2 is a top view thereof;

FIG. 3 is a front view thereof; and,

FIG. 4 is a side view thereof.

The rear view of the wash basin is a mirror image of the front view of the wash basin and is not illustrated in detail.
